CONTROL AND IGNITION SYSTEM FOR
FUEL BURNERSCharles K. Strobel, Pittsburgh, Pa., assignor to
Robertshaw-Fulton Controls Company, a cor-
poration of Delaware

Application March 13, 1946, Serial No. 654,202

7 Claims. (Cl. 158—117.1)

1

This invention relates to control and ignition systems for fuel burners and, more particularly, to electrically operated systems therefor.

Space heating fuel burner systems may include an electrically operated safety control which is supplied with electrical energy from a thermocouple or thermopile during the normal running period of the burner and which utilizes energy from a source of commercial supply for resetting purposes. A system of this type may employ a single control device such as a solenoid valve of standard form for both safety and condition control and this valve may be deenergized whenever the room thermostat or the safety control requires a shutoff of the main burner.

Such systems may be of the completely recycling type or may utilize a normally constant burning pilot burner. In the completely recycling type the fuel flow to both the main and pilot burners is shut off whenever the room thermostat is satisfied and a complete ignition cycle is performed each time the thermostat calls for heat. On the other hand, the normally constant burning pilot burner arrangement does not undergo such a complete recycling and the system is ordinarily required to perform the ignition cycle only at the beginning of the heating season, it being understood, however, that this system also requires an ignition cycle should the safety control operate due to extinguishment of the pilot burner.

In either type of installation it is of great convenience if the householder or other user can stop and start the heating system by merely operating the room thermostat in a normal manner. Thus, the householder need not visit the burner installation at all to relight or extinguish the pilot burner. Hence, a primary object of this invention is to permit convenient shutdown or relighting of the pilot burner at any time that the user desires.

Another object of the invention is to make the system either completely recycling or of the constant burning pilot burner type by a simple alteration in the wiring connections.

Another object of this invention is to utilize a single electromagnetic valve for condition or safety control in conjunction with a gaseous fuel burner without requiring alteration or modification in standard forms of valves to adapt them for such uses.

Another object of the invention is to employ thermoelectric energy independent of any outside source for operating the safety control during the burner running period while utilizing energy from a commercial source of supply in con-

2

nection with this control during the starting period only.

Another object of the invention is to render the system self-starting and recycling as long as the main fuel and electric control devices are turned on.

Another object of the invention is to incorporate the required transformers for adjusting the voltages to different circuit elements while utilizing certain characteristics thereof for dual purposes where feasible.

Other objects and advantages will become apparent from the following description taken in connection with the accompanying drawing, which is a schematic view of a control and ignition system for a gaseous fuel burner embodying the invention.

Referring more particularly to the drawing, a main burner 10 is supplied with fuel by a main fuel pipe 12 in which a main fuel shutoff cock 14 is provided. The flow of fuel in the pipe 12 is also under the control of an electromagnetic valve 16 which is biased to closed position. Interposed between the main fuel cock 14 and the electromagnetic valve 16 is a T connection 18 having a reducing outlet to accommodate a conduit 20 for supplying fuel to a pilot burner 22 located adjacent the main burner 10. The flow of fuel in the conduit 20 is under control of a pilot burner valve 23 which may also be of the electromagnetic type.

The main burner valve 16 is preferably of standard commercial form having an operating coil 24 and armature 25 which are shown separated therefrom in the drawing for purposes of clarity in illustration. The armature 25 is pivoted at one end and is adapted to engage a relatively fixed contact 21 at the other end when attracted by the coil 24. As will be apparent hereinafter, the main burner valve 16 may be provided with a manual setting device for opening the valve in the event of a power failure and an automatic resetting device for superseding the manual control when the power supply is resumed.

As such types of manual set, automatic reset devices are well known to those skilled in the art, illustration of the details thereof has been omitted and further description is deemed unnecessary. As this description proceeds, it will be apparent that the coil 24 of the main burner valve 16 and the corresponding coil of the pilot burner valve 23 are assumed to be either energized or deenergized for the purpose of preventing flow of fuel to the main burner 10 and the pilot burner 22, respectively, and such energization is sufficient

to overcome the bias of the valves to closed position.

The main burner valve 16 is under safety control of an electromagnetic device designated generally by the reference numeral 26. This device comprises a horseshoe magnet 28 having an armature 30 movable between attracted and released positions relative to the pole faces thereof. A stem 32 has lost motion connection with the armature 30 and is reciprocable relative to 10 the horseshoe magnet 28 for moving the armature to released position under bias of a coil spring 34. The stem 32 is provided with an enlarged head 36 which is adapted to engage the armature 30 and to move it toward the pole 15 faces of the horseshoe magnet 28 against the bias of the spring 34. When the armature 30 is engaged with the pole faces of the horseshoe magnet 28, that is, in its attracted position, then a contact bar 37 carried by the stem 32 is positioned thereby so that first and second switch contact pairs 38 and 40 at opposite ends of the bar, respectively, are closed. It will be understood that these contact pairs both comprise the usual fixed and movable contacts.

The resetting movement of the armature 30 to attracted position is under control of an electromagnetic resetting device designated generally by the reference numeral 42. The resetting means comprises a magnet plunger 44 having a swivel connection 46 depending therefrom.

A transformer 43 cooperates with the plunger 44 to form the electromagnetic portion of the resetting device 42 and, to this end, the primary coil 45 of the transformer forms the operating coil for the magnet plunger 44. It will be understood that it is not essential that a transformer be employed for this purpose but is merely illustrative of the preferred form of this invention. The swivel connection 46 carries a coil spring 48 which serves to support one end of a pivoted lever 50 loosely on the connection 46. The opposite end of the lever 50 carries a movable contact forming one of a third pair of switch contacts 52 associated with the electromagnetic device 26. It will be observed that the lever 50 is spaced from the enlarged head 36 of the stem 32 when all the contact pairs 38, 40 and 52 are engaged. The arrangement is such that upon upward movement of the magnet plunger 44 as will occur upon attraction thereof by means to be described, the lever 50 will be rotated on its pivotal mounting causing the end carrying the movable contact pair 52 to engage the enlarged head 36 and reset the armature 30 to attracted position relative to the pole faces of the horseshoe magnet.

The electromagnetic safety device 26 is adapted to be energized by thermoelectric means for maintaining the armature 30 in attracted position after it has been reset to such position by the resetting means 42. As shown, the thermoelectric means comprises a thermocouple 54 exposed to the heat of a flame at the pilot burner 22 and connected by wires 56 and 58 to a winding 60 for the horseshoe magnet 28. It will be understood that the electromagnetic device 26 does not receive sufficient energy from the thermocouple 54 to attract the armature 30 into engagement with the pole faces of the horseshoe magnet 28 but that the resetting means 42 is relied upon for such operation. However, after the armature 30 has been thus reset the thermocouple 54 will generate sufficient energy to retain the armature 30 in attracted position provided that the pilot burner

22 is producing a flame. It is apparent that the resetting means, being no longer required, can then be deenergized as will hereinafter be explained.

The electromagnetic valve 16 is also under the control of a device responsive to changes in a condition to be controlled. As disclosed in this embodiment, this condition responsive device is designated generally by the reference numeral 62 and takes the form of a room thermostat comprising a bimetallic spiral 64 carrying an arm 66 provided with a pair of spaced contacts 68 and 70. The contact 68 is cooperable with a fixed contact 72 and the contact 70 is cooperable with the fixed contact 74. A heater coil 76 is provided for accelerating operation of the bimetallic spiral 64 and is connected thereto at one end and to the contact 21 at the opposite end.

The condition responsive arrangement is such that upon a drop in temperature of the space in which the thermostat 62 is located the bimetallic spiral 64 moves in a clockwise direction to engage contacts 70 and 74 and thereafter contacts 68 and 72; the contact arrangement being such that upon initial engagement of contacts 70 and 74 there still remains a gap between contacts 68 and 72. When the thermostat is satisfied the bimetallic spiral 64 will move in a counter-clockwise direction to disengage contacts 68 and 72 and thereafter to disengage contacts 70 and 74. The device thus provides a definite temperature differential for energizing and deenergizing the coil 24 of the main burner valve 16 as will hereinafter appear. Moreover, neither of the pairs of contacts 68, 72, or 70, 74 is required to make or break the full load of the main burner valve 16 thus reducing arcing and wear of the contacts. It will be understood that other commercially available forms of thermostatic devices could be substituted and that it is not essential that two contacts be employed for closing a single circuit for the main burner valve 16.

Means are provided for adjusting the thermostat 62 and are shown as comprising a lever arm 78 which is secured to the bimetallic spiral 64. The bimetallic spiral 64 is pivotally mounted at 80 so that upon movement of the lever arm 78 the bimetallic spiral 64 is rotated about the pivot point 80 thereby varying the temperature at which the engagement of the pairs of contacts 68, 72 and 70, 74 is effected. The lever arm 78 cooperates with a scale 82 carrying suitable indicia to indicate the temperature setting of the thermostat.

Secured to the arm 66 and insulated therefrom is a third contact 84 which is adapted to cooperate with a fixed contact 86 when the arm 66 moves to engage the contact pairs 68, 72 and 70, 74. In addition, a toggle switch 88 may be located adjacent to the thermostat 62 and is adapted to be normally engaged with a fixed contact 90. The toggle switch 88 is adapted to be opened by engagement with the arm 66 when the lever arm 78 is moved to the extreme left of the scale 82 which is the lowest temperature setting. In the so-called completely recycling type of system the toggle switch may be dispensed with inasmuch as the opening of contacts 84, 86 serves to de-energize the coil of the pilot burner valve 23.

Igniting means 92 for the pilot burner 22 are provided and may comprise a coil of high resistance wire adapted to become incandescent upon passage of electrical energy therethrough. The igniting means 92 is under control of a thermal

switch designated generally by the reference numeral 94 and having fixed and movable contacts 96 and 98, respectively. The thermal switch 94 is preferably of the bimetallic snap switch type and includes a bimetallic element 100 which serves to operate the movable contact 98 with snap action when heat is applied to the element causing it to warp. Such heat may be supplied by a heating coil 102 wrapped around or otherwise disposed in proximity to the element 100. It will be observed that the thermal switch 94 is adapted to be closed when the bimetallic element 100 is unheated and the contacts 96 and 98 are at such times engaged.

Electrical energy from a commercial source of supply is controlled by a double-pole main switch 104 connected to the line wires 106. Preferably, a transformer 108 is connected in the line to supply low voltage power for operation of the system. If desired, the usual fan and associated control 110 may be connected in the primary circuit of the transformer 108.

In the operation of the completely recycling type of control described the system is turned on by opening the main fuel cock 14 and closing the main switch 104, it being apparent that these devices could be interconnected for simultaneous operation if desired. As the description proceeds, it will become apparent that during the burner starting period the commercial energy is utilized for resetting the safety control and then dispensed with in this connection when the self-contained energy of the thermocouple becomes available during the running period. The commercial source is, however, still relied upon during the burner running period in connection with the condition control and serves to energize both the main and pilot burner valves and the heating coil 102. The various elements of the system are shown in the position which they occupy when the thermostat 62 is calling for heat. Fuel is being supplied to the pilot burner 22 through the conduit 20 connected to the main fuel pipe 12 and, likewise, fuel is being supplied to the main burner 10 through the pipe 12. As previously pointed out, a feature of this invention is that the system may be completely shut down at the end of the heating season by merely manipulating the room thermostat and if the main fuel cock 14 and main switch 104 are left in open and closed positions, respectively, then the system may again be placed in operation at the onset of cold weather by merely setting the room thermostat at the desired temperature.

Assuming that the pilot burner has been extinguished and that the temperature falls below the setting of the thermostat so as to cause initial engagement of the contact 84 with the fixed contact 86, then the following circuit is established: from the lower terminal of the secondary of transformer 108 to conductor 112, conductor 114, contact 86, contact 84, conductor 116, conductor 118, toggle switch 88, contact 90, conductor 120, conductor 122, primary coil 45 of transformer 43, conductor 124, contacts 98 and 96, conductor 126 and conductor 128 to the upper terminal of the secondary of transformer 108. As the primary coil 45 of transformer 43 is energized through the foregoing circuit due to the contacts 96, 98 of the thermal switch 94 being closed, then the secondary of this transformer is also energized. The igniting means 92 is connected in series circuit with the secondary of transformer 43 by conductors 130 and 132 and is thereby caused to be heated so as to be in con-

dition to ignite the pilot burner 22 upon opening of the pilot burner valve 23.

The energizing of the primary coil 45 of the transformer 43 also causes the magnet plunger 44 of the resetting device 42 to be picked up. The lever 50 is thereby rotated on its pivotal mounting and causes the third contact pair 52 to be opened. The lever 50 also engages the enlarged head 36 of the stem 32 of the electromagnetic device 26 and overcomes the bias of the coil spring 34 to reset the armature 30 in engagement with the pole faces of the horseshoe magnet 28. The contact arm 31 attached to the stem 32 simultaneously causes the first and second contact pairs 38 and 40, respectively, to be closed.

The closing of the second contact pair 40 causes energization of the coil of the pilot burner valve 23 through the following circuit: From the upper terminal of the secondary of transformer 108, conductor 128, contact pair 40, conductor 134, coil of pilot burner valve 23, conductor 136, conductor 120, contacts 90 and 88, conductor 118, conductor 116, contacts 84 and 86 and conductors 114 and 112 to the lower terminal of the secondary of transformer 108. The fuel which is supplied through the conduit 20 to the pilot burner 22 when the valve 23 is opened is ignited by the igniting means 92 to produce a flame at this burner.

Simultaneously with the energization of the coil of the pilot burner valve 23 an energizing circuit is established to the heating coil 102, as follows: from the upper terminal of the secondary of the transformer 108, conductor 128, contact pair 40, conductor 138, heating coil 102, conductor 140, conductor 120, contact 90 and toggle switch 88, conductor 118, conductor 116, contacts 84 and 86 and conductors 114 and 112 to the lower terminal of the secondary of transformer 108. The energization of the heating coil 102 causes it to heat the bimetallic element 100 and causes the latter to warp sufficiently to open the switch contacts 96 and 98. Thus, the circuit which includes the primary coil of the transformer 43 is opened and the magnet plunger 44 is no longer attracted. Since the secondary coil of this transformer 43 is also deenergized, the igniting means 92 which is in circuit therewith is likewise deenergized for the duration of the running period of the burner.

The pivotal movement of the lever 50 resulting from dropping of the magnet plunger 44 causes the third contact pair 52 to again be closed. However, if during this starting period the fuel from the pilot burner 22 is ignited by the igniting means 92, then the thermocouple 54 has been sufficiently heated by the pilot burner flame to energize the winding 60. The armature 30 will then remain in its attracted position relative to the pole faces of the horseshoe magnet 28 although the energy from the line wires 106 is no longer available due to opening of the thermal switch contacts 96, 98. The attracted position of the armature causes the first and second contact pairs 38 and 40 to remain closed. As the third contact pair 52 is also closed, then a circuit from the coil 24 of the main burner valve 16 is established as soon as the thermostat 62 has operated to close the contacts 68—74. This circuit may be traced as follows: from the lower terminal of secondary of transformer 108, conductor 112, conductor 142, contact pair 52, conductor 144, contact pair 38, conductor 146, contacts 74, 70, arm 66, contacts 66, 72, conductor 148, valve 75 coil 24 and conductor 150 to the upper terminal

of the secondary of transformer 108. The valve coil 24 being energized through this circuit, the armature 25 is attracted and will engage contact 21. Heater coil 76 remains short-circuited as long as the contacts 72, 68 are engaged. The main burner valve 16 will then be operated to open position and fuel will be supplied to the main burner 10 where it is ignited by the flame from the pilot burner 22. It should be noted that the second contact pair 40 being closed causes the heater coil 102 to remain energized and maintain the thermal switch 94 in its open position.

The system will remain in operation under control of the thermostat 62 and the safety device 26 as long as the pilot burner 22 continues to produce a flame and there are no power interruptions. Whenever the thermostat is satisfied the contacts 68, 72 thereof are first disengaged but the circuit for the coil 24 of the main burner valve 16 is maintained as long as the contacts 70, 74 remain engaged. The opening of contacts 70, 74 is accelerated by the provision of the heater coil 76 which is energized upon opening of contacts 68, 72 to supply heat for the bimetallic spiral 64. The coil 24 is then deenergized to release the armature 25 and cause the main burner valve 16 to close.

When the contacts 84, 86 of the thermostat 62 are opened then the coil of the pilot burner valve 23 is deenergized so that both the pilot valve 23 and the main burner valve 16 are closed to shut off the fuel supply to both the main burner 10 and the pilot burner 22. The heater coil 102 of the thermal switch 94 begins to cool immediately before the contact pair 40 is opened by release of the armature 30 due to cooling of the thermocouple 54. However, eventually the thermocouple 54 will cool sufficiently and cause contact pairs 38 and 40 to be opened and contact pair 52 to be closed.

In the event that the safety device 26 operates due to the flame from the pilot burner 22 becoming extinguished, then the thermocouple 54 cools so as to deenergize the winding 60 causing release of the armature 30 of the pole faces of the horseshoe magnet 28. The contact pairs 38, 40 are then opened by movement of the stem 32 under bias of the spring 34. Thus, the circuit of the main burner valve 16 is opened by the first contact pair 38 and the main burner valve 16 moves to closed position to shut off the flow of fuel to the main burner 10. Moreover, the opening of the second contact pair 40 causes deenergization of the heater coil 102 of the thermal switch 94 and also the deenergization of the coil of the pilot burner valve 23. However, the contacts 96, 98 of the thermal switch 94 do not close until after a purge period, the length of which is determined by the time required by the bimetal 100 to cool.

The complete recycling character of the system is now apparent. After the bimetallic element 100 of the thermal switch 94 has caused the contacts 96, 98 of this switch to close, then the sequence of operation is the same as described when the system is first turned on. As the use of electrical energy from an outside source is depended upon for resetting the safety device only during the short starting period then it is apparent that the system is adapted for safety operation in the event that a power failure occurs during the normal running period. As previously described, the electromagnetic valve 16 is preferably of the commercially available manual-set,

automatic-reset type and therefore to be manually moved to open position in the event that a power failure occurs causing this valve to be closed. The system will then operate under control of the thermostatic device 62 and upon resumption of the current supply the electromagnetic valve 16 is automatically reset from its manual-set position without interruption of the fuel flow if the room thermostat is still calling for heat. The current consumption is very low due to the brief nature of the starting period and the deenergizing of the igniter during the running period of the burner.

In some instances it may be desirable to utilize a normally constant burning pilot burner instead of a completely recycling type of control as previously mentioned herein. In this event the only change required in the system as previously shown and described is to connect a conductor across points A and B as shown in broken lines in the drawing. Such connection will serve to short-circuit the contacts 84, 86 of the thermostat so that in its ordinary operation during the heating season the coil of the pilot burner valve 23 would never be deenergized. However, provision may be made so that at the end of the heating season the coil of the pilot burner valve 23 can be deenergized by adjusting the thermostat to a preselected temperature setting which may be the lowermost position on the scale 82. Such a normal manipulation of the thermostat would cause the arm 66 thereof to operate the toggle switch 88 and disengage contact 90 to open the switch, whereupon the coil of the pilot burner valve 23 would be deenergized. Inasmuch as the contacts 68-74 of the thermostat would also be opened in this thermostat position, then the coil 24 of the main burner valve 16 would also be deenergized and the system would be completely shut down. Upon the householder desiring to put the system into operation again, the lever arm 78 would be moved to the desired temperature setting and, as soon as the thermostat called for heat, the system would again be placed in operation.

Ordinarily, the main fuel cock 14 and main switch 104 will be located in the basement near the furnace and may either be left in open and closed positions, respectively, all of the time or during the heating season only. If the former expedient is used, then the flow of fuel to the main burner 10, or to the pilot burner 22 also, will be shut off during the summer months by the electromagnetic valves alone and a small amount of power (no load value) will be consumed by the transformer continuously.

While the invention described herein provides a relatively simple system of condition and safety control and ignition for gaseous fuel burners, it will be apparent that many changes can be made in the arrangement and combination of parts and in the details of construction herein disclosed within the scope of the appended claims without departing from the spirit of the invention.

65 I claim:

1. In a control system for fuel burners having main and pilot burners and a source of electrical energy, the combination of first electrically operable means connected to the source and being movable between positions for controlling the supply of fuel to the main burner, second electrically operable means connected to the source and being movable between positions for controlling the supply of fuel to the pilot burner, a first electromagnetic device having separate pairs

of contacts operable for controlling the energization of said electrically operable means respectively, means responsive to a flame at the pilot burner for controlling the energization of said device, and a second electromagnetic device connected to said source and operatively associated with the first said device for resetting the same and causing operation of said contacts for energization of said second electrically operable means while maintaining said first electrically operable means deenergized.

2. In a control system for fuel burners having main and pilot burners and a source of electrical energy, the combination of first electrically operable means connected to the source and being movable between positions for controlling the supply of fuel to the main burner, second electrically operable means connected to the source and being movable between positions for controlling the supply of fuel to the pilot burner, a first electromagnetic device having separate pairs of contacts operable for controlling the energization of said electrically operable means respectively, means responsive to a flame at the pilot burner for controlling the energization of said device, a second electromagnetic device connected to said source and operatively associated with the first said device for resetting the same and causing operation of said contacts for energization of said second electrically operable means while maintaining said first electrically operable means deenergized, and timing means responsive to said resetting operation for causing deenergization of said second device after a predetermined period during which said flame responsive means has time to become heated, said contacts thereby being operated for causing energization of said first electrically operable means while maintaining said second electrically operable means energized.

3. In a control system for fuel burners having main and pilot burners and source of electrical energy, the combination of a main burner fuel control valve, a pilot burner fuel control valve, separate electrically operable means for respectively controlling said valves, an electromagnetic device having first, second and third contact pairs, said first and third pairs being separately operable for controlling the energization of said main burner valve, said second pair being operable jointly with the first pair and being adapted for controlling the energization of said pilot burner valve, thermoelectric means responsive to a flame at the pilot burner for controlling the energization of said device, means operable for resetting said device and causing operation of said contacts, said second pair being operated for energization of said pilot burner valve while said third pair is operated for maintaining said main burner valve deenergized, and timing means responsive to said resetting operation for rendering the last said means inoperable after a predetermined period during which said thermoelectric means has time to become heated, said third contact pair being thereby operated to cooperate with said first pair for energization of said main burner valve while said second pair maintains said pilot burner valve energized.

4. A control system for fuel burners having main and pilot burners and a source of electrical energy, comprising in combination, electrically operable means connected to the source and being movable between fuel flow preventing and permitting positions for controlling the supply of fuel to the main burner, thermomagnetic switch

10

means responsive to a flame at the pilot burner and operable between a first position for causing energization of said electrically operable means for movement thereof to flow permitting position and a second position for causing deenergization of said electrically operable means for movement thereof to flow preventing position, means for resetting said thermomagnetic switch means in said first position including a second electrically operable means energized from the source, means responsive to movement of said thermomagnetic switch means to said first position for causing deenergization of said second electrically operable means, control switch means responsive to changes in a condition to be controlled for controlling the energization of the first said electrically operable means for movement thereof between flow preventing and permitting positions independently of said thermomagnetic switch means, and manual adjusting means for setting said control switch means to cause deenergization of said first electrically operable means irrespective of said controlled condition.

5. A control system for fuel burners having main and pilot burners and a source of electrical energy, comprising in combination, electrically operable means connected to the source and being movable between positions for controlling the supply of fuel to the main burner, an electromagnetic device having contacts operable between open and closed positions for controlling energization of said electrically operable means for movement thereof between said positions, thermoelectric means responsive to a flame at the pilot burner for controlling the energization of said device, igniting means for said pilot burner, means for resetting said device to cause closure of said contacts and simultaneously causing energization of said igniting means including a second electromagnetic device energized from the source, timing means responsive to closure of said contacts for causing deenergization of said second device and said igniting means after a predetermined period during which said thermoelectric means has time to become heated by said flame, means including a thermostat responsive to changes in temperature to be controlled for controlling the energization of said electrically operable means for movement thereof between said positions independently of the first electromagnetic device, and adjusting means for setting said thermostat at its lowest temperature to cause deenergization of said electrically operable means irrespective of said controlled temperature.

6. A control system for fuel burners having main and pilot burners and a source of electrical energy, comprising in combination, electrically operable means connected to the source and being movable between positions for controlling the supply of fuel to the main burner, electrically operable means connected to the source and being movable between positions for controlling the supply of fuel to the pilot burner, means responsive to changes in a condition to be controlled for controlling the operation of said electrically operable means for the main burner, means for adjusting the setting of said condition responsive means, and means including a control switch associated with said condition responsive means and operative upon said adjusting means being moved to a preselected setting for electrically disconnecting both said electrically operable means to shut off the fuel supply to both the main and pilot burners.

7. A control system for fuel burners having

11

main and pilot burners and a source of electrical energy, comprising in combination, electrically operable means connected to the source and being movable between positions for controlling the supply of fuel to the main burner, electrically operable means connected to the source and being movable between positions for controlling the supply of fuel to the pilot burner, igniting means for the pilot burner connected in parallel circuit with said electrically operable means for the 10 pilot burner, means for deenergizing said igniting means after a predetermined time delay including a thermal switch having contacts for opening said parallel circuit, means responsive to changes in a condition to be controlled for controlling the operation of said electrically operable means for the main burner, said condition responsive means including a pair of contacts operative for opening the circuit of said electrically operable means for

5

the main burner, means for adjusting the setting of said condition responsive means, and means including a control switch for opening the circuit of said electrically operable means for the pilot burner, said last means being cooperable with said pair of contacts upon said adjusting means being moved to a preselected setting for electrically disconnecting both said electrically operable means to shut off the fuel supply to both the main and pilot burners.
